UNITED STATES PATENT OFFICE

GEORGE P. SCHMITT, OF OAKLAND, CALIFORNIA

PAPER CLIP

Application filed October 8, 1928. Serial No. 311,040.

The invention relates to an improved clip or fastener for papers and the like.

An object of the invention is to provide a clip which is arranged to effect a particularly positive and releasable retention of papers therein.

Another object of the invention is to provide a paper retaining means which may be readily incorporated in clips of present structure without requiring the use of additional material therein or the use of attachments therefor.

The invention possesses other objects and features of advantage, some of which, with the foregoing, will be set forth in the following description of a preferred form of the invention and in the accompanying drawings, in which:

Figure 1 is a perspective view of a clip embodying the invention.

Figure 2 is an edge view of the clip.

Figure 3 is a perspective side view of the clip as it appears in use for binding a number of sheets together.

Figure 4 is a perspective edge view of the clip in use as in Figure 3.

Figure 5 is a view similar to Figure 3, but showing a different application of the clip.

As herewith particularly shown, the device of my invention is applied to a clip 5 constructed of a single piece of resilient wire convoluted to form substantially U-shaped and flat clamp members 6 and 7 connected by an intermediate U-shaped loop 8 of the wire.

The member 6 is defined by an end portion 9 of the wire connected to an opposed wire portion 11 by means of a bend 12, and the member 7 is correspondingly formed with sides 13 and 14 connected by a bend 15. As shown, the member 6 is slightly smaller than the member 7 and is nestable within it whereby said members are arranged to be substantially coplanar and coextensive when the clip is not in use, as is particularly shown in Figures 1 and 2 of the drawings.

The sides 16 and 17 of the connecting loop 8 are respectively coterminous with the clamp sides 11 and 14 respectively, and said loop is angularly related to the planes of the members 6 and 7, bends 18 and 19 being provided

at the juncture points of the loop sides with said clamp sides for effecting said relation of the clip parts. The bends 18 and 19, it will be particularly noted, are provided laterally opposite the adjacent wire extremities 21 and 22 respectively, and said extremities are preferably formed to provide distinct peripheral edges at the wire end. In the present instance, the wire is cut off square to provide a right-angled edge therearound, it being noted that the use of a special point forming means is thus avoided.

The bends 18 and 19, it will now be clear, cooperate with the wire extremities 21 and 22 to define a line of demarcation between the clamp members 6 and 7 and the loop 8, said line being conveniently considered as defining the inner edge of the clamp members and the base of the loop. Furthermore, for convenience, that side of the space occupied by the clamp members from which the loop 8 extends will hereinafter be referred to as the forward side of the clip, whereby the loop 8 may be said to extend obliquely forwardly from the members 6 and 7.

In using the clip now described, a number of sheets of paper or other sheet material would be inserted between the clamp members 6 and 7 from the free ends thereof by springing said members apart, the edges of said sheets at the clip extending into and obliquely through the loop 8. As particularly disclosed in Figures 3 and 4, the clip is operatively disposed for clamping together a front sheet 23 and one or more underlying sheets 24, with the larger clamp member 7 disposed in front of the sheet 23 and the other clamp member 6 lying behind the rear-most sheet 24. Owing to the oblique forward protrusion of the loop 8, the various sheets are bent forwardly out of their plane by reason of the engagement of the loop portion 16 therewith whereby the sheets are more or less sharply bent over the extremity 21 of the clip portion 13. This bending of the sheets in itself tends to further clamp the sheets together to resist their removal from the clip, but if a sheet removing force sufficient to overcome the frictional grip provided be exerted for removing a sheet, the sharp

edge of the extremity 21 will be brought to bear against the surface of the outer sheet 23 and removal thereof and of the other sheets will be additionally resisted. In fact, so effective is the engagement provided that the sheets will be torn by the extremity 21 before a removal thereof longitudinally of the clip may be effected, and the sheets are thus positively retained within the clip against an accidental disengagement thereof. For removing the clip from the sheets, a most convenient method is to effect opposite rotations of the clip and sheets in their common plane and about a point approximately at the extremity 21 for generally reversing the relation of the clip to the sheets whereby the clip and sheets may be separated without either of the wire extremities 21 or 22 being forced into the sheets against which they laterally bear.

As particularly shown in Figure 5, the clip is disposed with the smaller clamp member 6 in front of the forward sheet 23 and the other member 7 behind the rearmost sheet 24. In this case, the wire extremity 22 cooperates with the loop portion 17 for providing the desired grip on the sheets, the other extremity 21 being then inoperative except as forming part of the clamp member 7. In this manner, the clip is arranged to be equally operative in whichever way it is mounted for holding sheets together, it now being clear that the operation of my device is essentially that of the coaction of but one wire extremity with an opposed loop portion, and that if the clip be always engaged with sheets in the same relation, the disposition and shape of the wire extremity not used as a stop means is generally immaterial.

While I have herewith particularly disclosed the clip as formed of a piece of wire of circular section, it will be obvious that a clip embodying the invention might well be made of a strip of suitable resilient material of other than circular section. And it will be further evident that the device of my invention may be readily applied to a number of other existing types of clips without departing from the spirit of said invention.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the appended claim.

Having thus described my invention, I claim as new and desire to secure by Letters Patent of the United States the following:

A paper clip constructed of resilient wire to provide two substantially plane clamping members having base edges thereof defined at lines through the free ends of the wire and a substantially plane connecting loop having its plane intersecting at a sharp angle to the plane of a member at the base line thereof.

In testimony whereof, I affix my signature.

GEORGE P. SCHMITT.
